UNITED STATES PATENT OFFICE

HARRY I. LEASE, OF WHARTON, TEXAS

DESIGN FOR A WAYSIDE INN

Application filed January 13, 1930. Serial No. 34,121. Term of patent 14 years.

To all whom it may concern:

Be it known that I, HARRY I. LEASE, a citizen of the United States, residing at Wharton, in the county of Wharton and State of Texas, have invented a new, original, and ornamental Design for a Wayside Inn, of which the following is a specification, reference being had to the accompanying drawing forming a part thereof.

The accompanying drawings show my new design for an inn:

I claim:

The ornamental design for a wayside inn as shown.

HARRY I. LEASE.
